OSCILLATOR CIRCUIT

Robert C. Cheek, Irwin, Pa., assignor to Westinghouse Electric Corporation, East Pittsburgh, Pa., a corporation of Pennsylvania

Application June 23, 1949, Serial No. 100,808

5 Claims. (Cl. 250—36)

1

My invention relates to electronic circuits, and particularly to oscillators of the capacitance tuned type.

The plate output voltage of a conventional capacitance tuned oscillator of the Colpitts type decreases as the frequency of the oscillator is decreased. Such a characteristic is undesirable in most oscillator applications.

For example, in a conventional capacitance tuned superheterodyne radio receiver, the output of all the tuned stages decreases as the receiver is tuned toward the low end of the frequency band. This results in a decrease in gain which is emphasized where the mixer includes a local oscillator of the capacitance tuned type whose output decreases as it is tuned toward the low end of its frequency range. In this application, it would be desirable to have a local oscillator whose output would increase toward the low end of the frequency band in such a manner as to compensate for the decreased gain in the tuned stages of the receiver, thus giving the receiver a substantially constant gain over its entire tuning range.

In other oscillator applications, such as in signal generators, it is desirable that the oscillator output be substantially constant over its frequency range.

It is, accordingly, an object of my invention to provide an oscillator which will have a substantially constant output over a desired frequency range.

A further object of my invention is to provide a capacitance tuned oscillator having a controllable voltage output characteristic.

It is another object of my invention to provide an oscillator having a controlled output characteristic.

It is also an object of my invention to provide a capacitance tuned oscillator whose output voltage decreases as the frequency of oscillation increases, according to a predetermined pattern.

My invention, together with additional objects and advantages, will best be understood from the following description, when read in connection with the accompanying drawing, in which:

Fig. 1 is a schematic circuit diagram of a conventional capacitor tuned oscillator.

Fig. 2 is a schematic circuit diagram of a preferred embodiment of my invention.

Fig. 3 is a group of curves showing, non-quantitatively, several output characteristics of capacitance tuned oscillators to aid in the description of my invention.

Fig. 4 is an equivalent circuit of Fig. 1, and

Fig. 5 is an equivalent circuit of Fig. 1 modified. The conventional type capacitance tuned oscil-

2

lator shown in Fig. 1 includes an oscillator tube 11 having an anode 13, cathode 15 and a grid 17. The anode 13 is connected through an R. F. choke 19 to the positive terminal 21 of a plate voltage supply. A pair of ganged variable capacitors 23, 25 are connected from the anode 13 through a blocking condenser 27 to the grid 17 of the oscillator tube 11. The common junction 29 of the ganged capacitors is connected to the cathode 15 of the oscillator tube 11 and to ground 31. The conventional grid leak resistor 33 is connected between the common junction 29 of the blocking condenser 27 and the grid 17 of the oscillator tube 11 and ground 31. A tank inductance coil 35 is connected in parallel with the ganged capacitors 23, 25.

It is the usual practice in tuning oscillators of the conventional type just described, to fix the value of the ganged capacitors at some definite ratio and to vary the tank circuit inductance, or to maintain the inductance at a fixed value and make the ganged capacitors the variables. Because of the difficulty of providing suitable variable inductances, the latter arrangement is usually preferred. In this case, as the oscillator is tuned toward the low end of its frequency band, the output voltage appearing between plate and cathode will decrease, resulting in a characteristic such as that shown by curve (a) of Fig. 3.

My invention arises from the realization that the drooping oscillator output voltage characteristic is a result of a decrease in the tuned tank-circuit impedance as the oscillator is tuned toward the low end of its frequency band. This realization led me to an investigation of the feedback characteristics as related to the tank circuit arrangement of a conventional capacitor tuned oscillator of the Colpitts type.

My invention can best be explained with the aid of a mathematical analysis of some of the characteristics of a capacitance tuned Colpitts oscillator. In particular, it is desirable to investigate the relationship of variations in tank circuit capacitance to the amount of feed-back voltage obtained for a particular oscillator frequency.

Due to the complicated nature of the functions involved as a result of operation in the saturation regions of the oscillator tube characteristics, this analysis is qualitative and does not treat all possible phenomena in the case, but will serve to illustrate my invention.

With reference to Fig. 4, the grid-cathode and plate-cathode capacitors of the oscillator shown in Fig. 1 are C_1 and C_2 respectively. The oscillator tank circuit inductance and its resistance

55

are represented by L and r , respectively. The plate resistance of the oscillator tube is r_p . The grid-cathode voltage is e_g . The voltage across C_2 , represented by e_o , is the plate output voltage. The voltage across C_2 and r_p , represented by $-\mu e_g$, is the internally generated output voltage of the oscillator tube.

If the impedance looking into the oscillator tank circuit across C_2 is called Z_o , then since:

$$\frac{-\mu e_g}{e_o} = \frac{r_p + Z_o}{Z_o}$$

the plate output voltage may be expressed:

$$(1) \quad e_o = \frac{-\mu e_g Z_o}{r_p + Z_o}$$

The total resonant impedance of the tank circuit is QwL .

In a tapped parallel resonant circuit such as the tank circuit of Fig. 4:

(2)

Impedance offered to input (Z_o) =
Total resonant impedance (QwL) =

$$\left(\frac{C_1}{C_1 + C_2} \right)^2 \omega C_1 = \frac{1}{X_{C_1}} \text{ and } \omega C_2 = \frac{1}{X_{C_2}}$$

Substituting in (2)

$$\frac{Z_o}{QwL} = \left(\frac{\frac{1}{X_{C_1}}}{\frac{1}{X_{C_1}} + \frac{1}{X_{C_2}}} \right)^2 = \left(\frac{X_{C_2}}{X_{C_1} + X_{C_2}} \right)^2$$

$$(3) \quad Z_o = \left(\frac{X_{C_2}}{X_{C_1} + X_{C_2}} \right)^2 QwL$$

But:

$$Q = \frac{wL}{r} \text{ and } wL = X_{C_1} + X_{C_2}$$

Then substituting in (3)

$$(4) \quad Z_o = \frac{X_{C_2}^2}{r}$$

Substituting (4) in (1)

$$(5) \quad e_o = \frac{-\mu e_g X_{C_2}^2}{r \left(r_p + \frac{X_{C_2}^2}{r} \right)}$$

Substituting

$$\frac{1}{wC_2}$$

for X_{C_2} in (5)

$$(6) \quad e_o = \frac{-\mu e_g}{w^2 C_2^2 r r_p + 1}$$

Since the expression $w^2 C_2^2 r r_p$ is very large compared to 1 in (6), the 1 may be neglected and (6) may be written:

$$(7) \quad e_o = \frac{-\mu e_g}{w^2 C_2^2 r r_p}$$

But

$$w = \frac{1}{\sqrt{\frac{L C_1 C_2}{C_1 + C_2}}}$$

Substituting for w in (7):

$$(8) \quad e_o = \frac{-\mu e_g L C_1}{(C_1 + C_2) C_2 r r_p}$$

It is apparent from examination of Equation 8 that the value of e_o will increase more rapidly if C_1 alone is increased than if C_1 and C_2 are simultaneously increased while the ratio of C_1 to C_2 is

kept constant. Although variation of C_1 affects the value of μe_g , this effect is minimized by the fact that the grid of the oscillator tube is operated in the region of saturation.

5 This means that if C_1 alone is increased, as the oscillator is tuned toward the low end of its frequency range, the oscillator output voltage will tend to increase, resulting in a characteristic similar to curve (c) of Fig. 3. On the other hand, 10 if both C_1 and C_2 are varied to tune the oscillator toward the low frequency end of its range, the output voltage will tend to decrease, giving a characteristic curve similar to curve (a) of Fig. 3.

15 Thus I have found that by tuning only the grid-cathode capacitor in an oscillator such as the one shown in Fig. 1, I can obtain an output voltage characteristic which rises toward the low end of the oscillator frequency range to compensate in 20 such applications as local oscillator in a super-heterodyne receiver, for the drooping characteristics of succeeding stages.

I have further found that by placing an additional capacitance of the proper value in series 25 with the tank coil of the oscillator, I can accurately control the slope of the output voltage characteristic. This aspect of my invention may be analyzed mathematically with reference to Fig. 5, which is an equivalent circuit identical 30 to Fig. 4 except that a capacitor C_4 has been added in series with the tank inductance coil.

The plate output voltage may be expressed:

$$(9) \quad e_o = \frac{-\mu e_g Z_o}{r_p + Z_o}$$

as in (8).

$$(10) \quad Z_o = \frac{QwL X_{C_2}^2}{(X_{C_4} + X_{C_1} + X_{C_2})^2}$$

40 But

$$Q = \frac{wL}{r}$$

and

$$wL = X_{C_4} + X_{C_1} + X_{C_2}$$

45 Then substituting in (10):

$$(11) \quad Z_o = \frac{X_{C_2}^2}{r}$$

50 as in (4).

Substituting (11) in (9).

$$(12) \quad e_o = \frac{-\mu e_g}{w^2 C_2^2 r r_p}$$

55 as in (7).

But

$$w = \sqrt{\frac{1}{\frac{L C_1 C_2 C_4}{C_1 + C_2} + \frac{C_1 C_2}{C_1 + C_2} + C_4}}$$

$$60 \quad (13) \quad = \frac{1}{\sqrt{\frac{L C_1 C_2 C_4}{C_1 C_2 + C_1 C_4 + C_2 C_4}}}$$

Substituting (13) in (12):

$$70 \quad (14) \quad e_o = \frac{-\mu e_g L C_1 C_4}{(C_1 C_2 + C_1 C_4 + C_2 C_4) C_2 r r_p}$$

Since

$$(15) \quad e_g = \frac{e_o C_2}{C_1}$$

Substituting (14) in (15) and for simplification, taking $\mu e_g = 1$

$$(16) \quad e_s = -\frac{LC_s}{(C_1C_2 + C_1C_s + C_2C_s)rr_p}$$

or:

$$(17) \quad e_s = -\frac{L}{\left(C_1 + C_2 + \frac{C_1C_2}{C_s} \right)rr_p}$$

Without the series capacitor C_s , Equation 17 would become:

$$(18) \quad e_s = -\frac{L}{(C_1 + C_2)rr_p}$$

By comparison of Equations 17 and 18, it will be seen that with C_s in the circuit, as C_1 is increased to tune the oscillator toward the low end of the frequency range, the value of e_s will decrease more rapidly than if C_s were not in the circuit. This means that by using C_s it is possible to obtain an oscillator output voltage characteristic which is substantially flat, such as the one shown by curve (b) of Fig. 3. By choosing the proper value of C_s it is possible to obtain substantially any desired oscillator voltage output characteristic.

In accordance with a preferred embodiment of my invention, I provide an oscillator circuit as shown in Fig. 2. This oscillator circuit includes an oscillator tube 37 having an anode 39, a cathode 41 and a grid 43. A radio frequency choke 45 is connected from the anode 39 of the oscillator tube 37 to the positive terminal 47 of an anode voltage source. A first 49 and second 51 fixed capacitor are connected in series from the anode of the oscillator tube through a blocking condenser 53 to the grid 43 of the oscillator tube 37. The conventional grid leak resistor 55 is connected between the junction 57 of the blocking condenser 53 and the grid 43 of the oscillator tube 37 and ground 59. A variable capacitor 61 is connected in parallel with the fixed cathode grid capacitor 51. A tank inductance coil 63 in series with a third fixed capacitor 65 is connected in parallel with said first 49 and second 51 fixed capacitor.

This oscillator is tuned by varying only the grid cathode capacitance. While it is within the broad scope of my invention to have only one grid cathode capacitance, that being a variable capacitance, the use of a plurality of paralleled grid-cathode capacitances, properly proportioned, permits the desired frequency band to be spread over the entire range of the tuning control.

With a circuit such as the one just described, the value of the third fixed capacitor 65 which is connected in series with the tank inductance coil may be chosen so as to adjust the output versus frequency characteristic of the oscillator as required, so that with the proportion of the cathode-anode 49 and the cathode-grid 51, 61 capacitors such that the desired frequency range is obtained, the desired output characteristic is obtained. Increasing the value of the third fixed capacitor 65, with corresponding decrease in the value of the cathode-anode capacitor 49 will provide a more dropping characteristic with a given decrease of the variable cathode grid capacitor 61 and vice versa. The third fixed capacitor 65 has the additional desirable effect of decoupling the oscillator tank circuit to some extent from the oscillator tube 37, making the frequency of the oscillator less sensitive to variations in the inter-electrode capacitances in the tube and resultant

changes in frequency caused by supply voltage variations.

For use as the local oscillator in a superheterodyne receiver where it is desirable to have the oscillator output increase toward the low end of the oscillator frequency band to compensate for a corresponding decrease in gain of the various receiver stages, I have used the following circuit constants to obtain an oscillator output voltage characteristic similar to that shown by curve (c) of Fig. 3:

Grid leak resistance 55... 100,000 ohms.
Grid blocking capacitor 100 micro-microfarads.
53. Fixed cathode grid ca- 75 micro-microfarads. capacitance 51.
Variable grid cathode 5 to 28.5 micro-micro-
capacitance 61. farads.
20 Fixed anode-cathode ca- 47 micro-microfarads.
capacitance 49.
Tank inductance..... 2.5 micro-henries (ap-
prox.).
Series capacitance 65... 57 micro-microfarads.

25 By the proper selection of circuit constants, it is possible to obtain an oscillator output voltage characteristic which rises at a desired slope toward the low end of the oscillator frequency band for application such as the one just illus-
30 trated, or to obtain a substantially constant char-
acteristic for applications, such as in a signal
generator, where that is desirable. In addition
35 to making possible the selection of any desired
oscillator output voltage characteristic, my in-
vention has the advantage of replacing the
variable cathode-anode capacitor 25 of Fig. 1 of
the prior art capacitance tuned Colpitts oscil-
40 lator circuits with a fixed capacitor 49 of Fig. 2.
This results in a reduction of cost of the oscil-
lator as well as a saving in space.

While I have shown and described a specific embodiment of my invention, I am fully aware that many modifications thereof are possible. My invention, therefore, is not to be restricted except
45 in so far as is necessitated by the prior art and by the spirit of the appended claims.

I claim as my invention:

1. An oscillator comprising an electric dis-
charge device having at least an anode, a cathode,
50 and a grid, terminals for connection to a source
of anode potential, an inductance connected
between said anode and grid, a capacitance con-
nected in shunt with said anode and cathode,
55 and a plurality of paralleled capacitances, at least
one of which is variable, connected between said
grid and cathode.

2. An oscillator comprising an electric dis-
charge device having at least an anode, a cathode,
and a grid, terminals for connection to a source
60 of anode potential, an inductance and capacitance
connected between said anode and grid, a capaci-
tance connected in shunt with said anode and cathode,
and a plurality of paralleled capaci-
65 tances, at least one of which is variable, con-
nected between said grid and cathode.

3. An oscillator comprising an electric dis-
charge device having an anode, a cathode, and
a grid, terminals for connection to a source of
anode potential, a tunable circuit comprising an
70 inductive reactance in series with a first capaci-
tive reactance and connected in shunt with a
second capacitive reactance, said second capaci-
tive reactance being connected in shunt with said
anode and cathode, connections from the junc-
75 tion of said inductive reactance and first capaci-

tive reactance to said grid, said first capacitive reactance including paralleled capacitance at least part of which is variable.

4. An oscillator comprising an electric discharge device having an anode, a cathode and a control electrode, terminals for connection to a source of anode potential, a series circuit including a tuning inductance, a first capacitor, a second capacitor, and a capacitive reactance at least part of which is variable, means for connecting 10 the junction of said inductance and said capacitive reactance to said control element, means for connecting the junction of said first and second capacitors to said anode, and means for connecting the junction of said capacitive reactance and said second capacitor to said cathode.

5. An oscillator comprising an electric discharge device having an anode, a cathode and a control electrode, terminals for connection to a source of anode potential, a series circuit includ- 15

ing a tuning inductance, a first capacitor, a second capacitor, and a variable capacitor, means for connecting the junction of said inductance and said variable capacitor to said control element, means for connecting the junction of said first and second capacitors to said anode, and means for connecting the junction of said variable capacitor and said second capacitor to said cathode.
